UNITED STATES PATENT OFFICE.

JOSEPH OSCAR WILD, OF HOLYOKE, MASSACHUSETTS.

SODA-WATER APPARATUS.

SPECIFICATION forming part of Letters Patent No. 656,072, dated August 14, 1900.

Application filed January 4, 1900. Serial No. 340. (No model.)

To all whom it may concern:

Be it known that I, JOSEPH OSCAR WILD, residing at Holyoke, in the county of Hampden and State of Massachusetts, have invented a new and Improved Soda-Water Apparatus, of which the following is a specification.

My invention is an improvement in soda-water apparatus, seeking especially to provide novel constructions by which to conveniently dispense the syrups used in such apparatus; and the invention consists in certain novel constructions and combinations of parts, as will be hereinafter described, and pointed out in the claims.

15 In the drawings, Figure 1 is a perspective view of my apparatus as in use. Fig. 2 is a side view thereof, part in section. Fig. 3 is a cross-sectional view on about line 3-3 of Fig. 2. Fig. 4 is a detail view illustrating the door for preventing the withdrawal of the syrup vessels. Fig. 5 is a detail view illustrating a modified form of such door. Fig. 6 is a detail view of the turn-table plate for carrying the tumblers. Fig. 7 is a cross-sectional view 25 illustrating an apparatus in which the doors immediately outside the syrup vessels are omitted, and Fig. 8 illustrates in detail the syrup vessels employed when the outer doors are omitted.

30 The central holder A is mounted upon a base B and is designed to contain ice or other cooling medium, and the soda-dispensing devices may lead through such central holder, as shown, or be otherwise disposed in any 35 suitable manner. Upon its outer side the holder A is provided with a shelf-like support C, upon which rests the turn-table plate D, which revolves upon the plate C and forms a revolving carrier for the vessels E, which 40 are the syrup-jars, as shown, and which may be made of any suitable material. Where desired, balls may be interposed between the plates C and D to reduce friction. At their lower ends the vessels E are provided with 45 depending discharge-nozzles e, having faucets provided with outwardly-projecting handles e', which may be operated when the particular vessel E is brought to the proper position, as will be presently described. Upon the 50 holder A, I support the top F, which is provided with a depending flange f, which overlaps the upper end of the vessels E, as shown.

A casing G is supported upon the base B and has at g a portion which overlaps the lower end of the vessels E and co-operates with 55 the flange f in preventing any outward displacement of the vessels.

It may be preferred to provide a separate compartment for each of the syrup-jars and to provide a separate door H for each of such 60 compartments, as shown in Figs. 1, 2, and 3. In this construction the upper and lower ends of the doors fit within the overlapping portions f and g of the cover F and casing G and are thus held from opening when not desired, 65 the doors being hinged at h and opening freely upon such hinges when not obstructed by the portions f and g before described.

At one side the casing G is provided with an opening g', which may be closed by a door g², 70 and whose upper end is extended at g³ to the top of the casing and coincides with an opening f' in the flange f. When a jar is brought into register with the openings f' and g³, it may be withdrawn for the purpose of refilling it or for any other purpose desired. To prevent the withdrawal of the jar except when desired, I provide a narrow door g⁴ for the opening g³. This door g⁴ may be hinged on a vertical pintle, as shown in Fig. 4, or may 75 be in the form of a hook-latch pivoted horizontally, as shown in Fig. 5.

In the operation of the described construction the turn-table plate D may be revolved to bring any desired syrup-jar to the position 85 shown in Fig. 1, where its contents may be drawn, by opening the faucet, into the glass below. It will be noticed that the casing G is provided at G² with an outwardly-bulged annular portion forming a passage-way for 90 the outwardly-projected handles e' of the faucets of the nozzles of the syrup-jars.

Where desired, the separate compartments and doors H may be omitted and the syrup-jars be arranged, as shown in Fig. 7, side by 95 side and with their outer faces exposed. In this case it may be desired to bevel the edges of the syrup-jars at H², as shown in Figs. 7 and 8.

The glasses are arranged upon a turn-table 100 plate I, which is provided with seats at I' for such glasses, as best shown in Fig. 6. This turn-table plate I is arranged within the casing G and upon the base B and may be

mounted upon balls, as shown in Fig. 2. As will be understood from Figs. 1 and 2, the plate I may be filled with glasses and readily turned to bring any desired glass into register with the opening G', as shown in Fig. 1.

5 The syrup-jars rest directly against the central holder and will be cooled thereby in operation. It is evident that by supporting the jars as described they can be conveniently brought into position for use and used without the necessity of handling the jars and that the construction as shown and described will greatly facilitate the dispensing of the drinks and will occupy but a small 15 counter-space.

The door g² may be hinged, as shown in Fig. 1, or such part may be arranged to slide, as shown at g¹² in Fig. 7.

Having thus described my invention, what 20 I claim, and desire to secure by Letters Patent, is—

1. The apparatus herein described comprising the base, the central holder having the shelf-like support on its outer side, the turn-table 25 plate encircling the central holder and resting upon the shelf-like support and adapted to receive the syrup vessels, the syrup vessels having depending outlet-tubes at their lower ends, a retaining device for the upper 30 ends of the syrup vessels, and a casing overlapping the lower ends of the syrup vessels and having an opening through which access may be had to the syrup vessels, substantially as set forth.

35 2. In an apparatus substantially as described, the combination of the base, the central holder having the shelf-like support on its outer side, the syrup vessels resting on said shelf-like support, the top carried by the 40 central holder and extending over and having portions depending outside the upper ends of the syrup vessels, and the casing resting upon the base and overlapping the lower ends of the syrup vessels substantially as set forth.

45 3. In an apparatus substantially as described, the combination of the syrup vessels, a rotating support therefor, said vessels having depending outlet-tubes provided with faucets having outwardly-projecting handles and 50 the casing overlapping the lower ends of the vessels and having a channel or passage-way for the handles of the faucets, substantially as set forth.

4. An apparatus substantially as described, 55 comprising the central holder, the turn-table plate encircling the holder and adapted to support the syrup vessels, and the turn-table for the glasses, such turn-table being concentric with that for the syrup vessels, substantially as set forth.

5. An apparatus substantially as described comprising the central holder, the turn-table

plate encircling the holder and adapted to support the syrup vessels, and the turn-table plate below said first turn-table plate and 65 adapted to support the tumblers, and the casing fitting over said plates and inclosing the space between the same substantially as set forth.

6. An apparatus substantially as described 70 comprising the central holder, the turn-table for the syrup vessels, the cover on said holder, the casing, both the cover and the casing having coincident openings, the compartments for the syrup vessels on said turn-table and 75 the doors to said compartments, such doors being held from opening except when opposite the coincident openings in the cover and casings, substantially as set forth.

7. An apparatus substantially as described, 80 comprising the central holder, the turn-table revolving around the same, the syrup vessels supported on said turn-table and retaining means overlapping the syrup vessels and having coincident openings through which the 85 syrup vessels may be withdrawn, substantially as set forth.

8. In an apparatus substantially as described, the combination of the turn-table for 90 the syrup vessels, the individual doors for said vessels, said doors being arranged to open and shut independently of their respective vessels and the casing having means by which to hold said individual doors closed except in certain adjustments thereof, substantially as set forth.

9. An apparatus substantially as described comprising the central holder, the base, a shelf-like support upon the outer side of the holder, a cover having a depending flange 100 overlapping the upper ends of the vessels, the casing upon the base and having at its upper end a portion overlapping the lower ends of the vessels, such portion and the depending flange of the cover having coincident openings through which the jars may be removed, the turn-table plate upon the base within the casing and adapted to support the glasses substantially as set forth.

10. In an apparatus substantially as described, the combination of the central holder, the top thereon having a depending flange, the casing having a portion adapted to overlap the lower ends of the jars, the jars, a turn-table support therefor, and individual doors 115 for each of said jars, said doors being movable to open and closed position independently of their respective jars, substantially as set forth.
